INCANDESCENT LAMP

John L. Kivari, Detroit, Mich.

Application August 30, 1949, Serial No. 113,090

3 Claims. (Cl. 315—70)

1

This invention relates to incandescent lamps, and more particularly to incandescent electric lamps of the screw-base type.

A main object of the invention is to provide a novel and improved incandescent lamp adapted for use with ordinary house-lighting circuits, said lamp employing a low-voltage filament and including means for reducing the line voltage to a relatively low voltage for application to said filament.

A further object of the invention is to provide an improved incandescent lamp which is characterized by relatively high light output efficiency, which is very durable, and which has a useful life which is not affected to any serious extent by fluctuations in the house-lighting line voltage.

Further objects and advantages of the invention will become apparent from the following description and claims, and from the accompanying drawings, wherein:

Figure 1 is a side elevational view, partly in cross-section, of an improved incandescent lamp constructed in accordance with the present invention;

Figure 2 is a schematic diagram illustrating the electrical connections of the lamp of Figure 1;

Figure 3 is an enlarged perspective detail view, showing a modified form of filament member constructed in accordance with the present invention;

Figure 4 is a cross-sectional detail view taken on line 4—4 of Figure 3.

Referring to the drawings, 11 generally designates an incandescent lamp, said lamp comprising an outer glass envelope 12 secured to a conventional screw-base 13, and enclosing a filament 14. As shown in Figure 1, the neck of the envelope 12 includes a transverse glass partition member 15 on which is mounted the glass riser 16 containing the lead-in wires 17 and 18. The filament 14 consists of a thin Tungsten circular shell transversely of and in encircling spaced relation with respect to the riser 16 and welded or otherwise rigidly secured at diametrically-opposite points to the respective lead-in wires 17 and 18. The lead-in wires 17 and 18 are relatively stiff, whereby the filament shell 14 is rigidly supported by said lead-in wires. Secured in the compartment defined in the neck of the envelope 12 below the glass partition wall 15 is a step-down transformer 19 whose secondary terminals are connected to the lead-in wires 17 and 18. One of the terminals of the primary of transformer 19 is connected by a wire 20 to the center contact 21 of the screw-base 13. The other secondary terminal of the transformer is connected by a wire

2

22 to the shell of said screw-base. The wiring connections are diagrammatically shown in Figure 2.

In operation, the input line voltage, say, 110 5 volts A. C., is impressed across the primary of the transformer 19, providing low voltage, of the order of one volt, across the secondary of the transformer. The secondary voltage is impressed on the thin Tungsten ring 14, causing said ring 10 to be heated to incandescence. The ring 14 has a relatively large surface area, and, therefore, provides a very large light output, the voltage applied thereto and the thickness thereof being such as to produce a high-current density in said 15 ring, and to maintain the ring at a relatively high temperature. Although a high current flows in the secondary circuit of the transformer 19, the current in the primary circuit is not excessive, due to the step-down characteristics of the transformer, and since the transformer efficiency is 20 relatively high, there is little loss due to the use of said transformer.

Figures 3 and 4 illustrate an alternative filament member comprising a cylindrical sleeve 23, 25 formed of thin Tungsten or the like and provided with internal stiffening rings 24, 24 at its respective ends. The sleeve 23 is connected to the lead-in wires 17 and 18 at its respective end portions transversely of and in perpendicular spaced relation with respect to the riser and is supported on the lead-in wires in the same manner as the rings 14 are supported on said wires in the embodiment illustrated in Figure 1. The thin filament sleeve 23 is heated up to incandescence by the secondary voltage applied thereacross from the transformer 30 35 19, a relatively high-current density being present in the sleeve, whereby a high operating temperature is obtained. Due to the large area of the sleeve, a very high light output is obtained per watt dissipated in the primary circuit of the transformer.

It is well known that the life of an ordinary incandescent lamp connected directly across the line of a house-lighting circuit may be severely reduced when the line voltage surges even momentarily, such surges frequently causing the lamp to immediately burn out. It has been found that the life of a lamp decreases very rapidly when the voltage applied across the filament is only a very small value above its rated voltage. 45 By providing the step-down transformer 19 in the lamp, the actual change of voltage across the filament of the lamp is very small as compared with the amount of voltage above rated value which a line surge may cause across the primary 50 of the transformer. Also, by employing the ring

shape, as shown in Figures 1 and 2, or the cylindrical shape, as shown in Figures 3 and 4, for the filament, said filament is made very rugged mechanically and will withstand severe shocks and vibratory forces, greatly increasing the mechanical durability of the lamp.

While certain specific embodiments of an incandescent lamp have been disclosed in the foregoing description, it is to be understood that various modifications within the spirit of the invention may occur to those skilled in the art. Therefore, it is intended that no limitations be placed on the invention except as defined by the scope of the appended claims.

What is claimed is:

1. An incandescent lamp comprising a screw base and including a pair of contact terminals, a glass envelope secured at one end to said base, a partition fixedly positioned transversely of and within said envelope and spaced from said base, a step-down transformer including a primary and secondary positioned within said envelope intermediate said partition and base and having the primary connected at the opposite ends thereof to said contact terminals, a riser positioned in the envelope and having one end secured to said partition, a pair of lead-in wires positioned in said riser and projecting from the opposite ends thereof, one of the projecting ends of said lead-in wires being secured to the secondary of said transformer, and an annular filament positioned transversely of and spaced from said riser adjacent the other end thereof and secured to the other projecting ends of said lead-in wires.

2. An incandescent lamp comprising a screw base and including a pair of contact terminals, a glass envelope secured at one end to said base, a partition fixedly positioned transversely of and within said envelope and spaced from said base, a step-down transformer including a primary and secondary positioned within said envelope intermediate said partition and base and having the primary connected at the opposite ends thereof to said contact terminals, a riser positioned in the envelope and having one end secured to said

partition, a pair of lead-in wires positioned in said riser and projecting from the opposite ends thereof, one of the projecting ends of said lead-in wires being secured to the secondary of said transformer, and an annular filament transversely of and in encircling spaced relation with respect to said riser adjacent the other end thereof and secured to the other projecting ends of said lead-in wires.

- 10 3. An incandescent lamp comprising a screw base and including a pair of contact terminals, a glass envelope secured at one end to said base, a partition fixedly positioned transversely of and within said envelope and spaced from said base, a step-down transformer including a primary and secondary positioned within said envelope intermediate said partition and base and having the primary connected at the opposite ends thereof to said contact terminals, a riser positioned in the envelope and having one end secured to said partition, a pair of lead-in wires positioned in said riser and projecting from the opposite ends thereof, one of the projecting ends of said lead-in wires being secured to the secondary of said transformer, and an annular filament transversely of and in encircling spaced relation with respect to said riser adjacent the other end thereof and secured to the other projecting ends of said lead-in wires.
